UNITED STATES PATENT OFFICE.

WILLIAM ARTHUR OUBRIDGE, OF COVENTRY, ENGLAND.

PISTON-RING-HAMMERING MACHINE.

1,336,153.

Specification of Letters Patent.

Patented Apr. 6, 1920.

Application filed November 20, 1918. Serial No. 263,263.

To all whom it may concern:

Be it known that I, WILLIAM ARTHUR OUBRIDGE, a subject of the King of Great Britain and Ireland, and residing at "Haldon," Park Road, Coventry, in the county of Warwick, England, have invented Improvements in Piston-Ring-Hammering Machines, and of which the following is a specification.

10 This invention relates to improvements in piston-ring hammering machines in which blows of a force that varies in intensity from the slit to the center and vice versa on the inner side of the ring or rings are imparted 15 by a chisel-like tool or tools.

According to this invention, the blows of varying force are delivered by a chisel-like tool fixed to a hammer head adapted to slide on a guide and the force imparted to the 20 hammer-head is varied by loading the hammer-helve, which is pivoted to the said head and is also pivoted at the opposite end, at varying points between the head and the tail of the helve.

25 An automatically driven means moves the load along the hammer-helve for varying the intensity of the blows of the chisel-like tool, from the minimum to the maximum and vice versa, and means may be further 30 provided for adjustment of the range of the movements of the load relatively to the movement of the rings.

In addition to the load position varying means, a member moving synchronously 35 therewith may cause the disengagement of the driving-clutch or the like to stop the operation of the machine when a series of blows has been completed.

In order that my invention may be properly understood the following is a description 40 of one embodiment thereof having reference to the accompanying drawings, in which—

Figure 1 is a front view of the machine 45 selected as example.

Fig. 2 is a plan, partly in section, of the machine shown in Fig. 1.

Fig. 3 is a transverse vertical section on the line 3—3 Fig. 1, and

50 Fig. 4 is a front view of the chuck for holding piston rings.

In this embodiment of the invention the sliding hammer-head 1, carrying the chisel-like tool 1^a, is caused to rebound just clear 55 of its work after a blow, by means of a

spring 2 and is lifted to a uniform height to import each blow by a snail-cam 3 which engages a wiper 4 fixed to the head 1 for this purpose.

The hammer-helve 5 is pivoted at 6, carried by a standard 6^a on the machine frame and has a slot 7 adapted to allow the lengthwise movement necessitated by the straight line motion of the hammer-head 1 to which also it is pivoted at 8.

The varying leverage of the load, moved along the hammer-helve 5, is effected by means of a heart-cam 9 formed to correspond with the intensity of blows required at the different parts of a ring. This cam 9 reciprocates a bar 10 which bar carries a guide 11 arranged transversely thereon and in which guide slides a roller bearing 12 through which the hammer-helve 5 passes and which is constantly pulled in the direction to press on the said helve 5 and force the hammer-head toward its work, the pulling being effected by a helical spring 13 fixed at one end to a lug 14 carried on the guide 11 and at the other end to a hook 12^a 80 fixed to the roller bearing 12. To allow the loading to be varied an anti-friction bar-roller 15 is carried by the bar 10 and is adjustable transversely thereof along a cross-bar 16 for graduating the relative force of 85 all the blows in a series of blows, and the heart-cam 9 transmits a reciprocal movement to the said anti-friction bar-roller 15 and consequently to the bar 10 which carries it, by means of a lever 17 which it oscillates 90 through a lever-roller 18 mounted thereon.

By adjusting the bar-roller 15 along the lever 17 and setting it on the cross-bar by tightening the nuts 16^a and thereby causing the screws to force the slide 16^b and V-strip 95 16^c against the cross-bar 16 to grip it, the travel of the bar may be increased or diminished and the range of blows on a ring, held in a piston-ring chuck 50 carried in a chuck-bearing 19, correspondingly 100 increased or diminished, respectively. The said bar-roller 15 is kept against the lever 17 by the pull of a weighted cord 20, which passes over a pulley 21, so that the lever-roller is in turn constantly pressed against 105 the said heart-cam 9.

A worm-wheel 33 on the heart-cam pin 22 carries a clutch-cam 23 which rotates synchronously with its and which, when a series of blows varying from the minimum to the 110

maximum, and vice-versa, has been delivered, allows a clutch lever-roller 24 to drop into a notch 25 in the said cam 23 and so release the driving clutch 26 and stop operation of 5 the machine.

The machine is driven by means of a loose pulley 27 which rotates its shaft 28 when a friction disk 29, feathered on the said shaft 28, is operated, which shaft 28 has worms 30 10 and 31 in gear with worm-wheels 33 and 34. The former rotates on the fixed pin 22 and has the heart-cam 9 and clutch-cam 23 fixed to it. The latter worm-wheel 34 is integral with the ring chuck 50, and this worm-shaft 28 drives, through toothed wheels 35 and 36, 15 a second shaft 37 for operating the snail-cam 3 which raises the hammer-head 1.

The piston-ring chuck 50 (see Figs. 3 and 4) preferably comprises a removable bed-ring 38 fixed in the chuck 50 and recessed annularly to receive the piston-ring or rings, for example such as that indicated at 39, to be operated upon and a cover-ring 40 adapted to be pressed against the piston-ring, when the latter is in place, by handled nuts 41, 41 engaging studs 42, 42 fixed to the chuck. In Fig. 3 a stud and nut are displaced to show the construction. These nuts engage the outer side of the cover-ring 30 40 near its outer periphery and are used to force the covering 40 and bed-ring 38 one toward the other for gripping the piston-ring or rings between them. The nuts 41, 41 are provided with handles or knobs 41^a, 41^a 35 for easy manipulation and the cover-ring 40 is recessed at 43, 43 and furnished with a spider-handle 44 so that by rotating it until the said recesses 43, 43 register with the nuts 41, 41 it may be easily inserted or removed.

I claim:—

1. A piston ring hammering machine comprising in combination, a hammer-head, a hammer-helve connected thereto at one end 45 and pivoted to a relatively stationary part of the machine at its other end, means for holding a piston-ring in position for being hammered by said hammer-head, a loading means for said hammer-helve, means for 50 varying the position of said loading means along said hammer-helve and means for reciprocating said hammer-head substantially as described.

2. A piston ring hammering machine comprising in combination, a hammer-head, a hammer-helve connected thereto at one end and pivoted to a relatively stationary part of the machine at its other end, means for holding a piston-ring in position for being 55 hammered by said hammer-head, a loading means for said hammer-helve, means for varying the position of said loading means along said hammer-helve and means for reciprocating said hammer-head and mechanism actuated together with the hammering 60

machine for automatically moving said loading means along the hammer-helve, substantially as described.

3. A piston ring hammering machine comprising in combination, a hammer-head, 70 means for reciprocating said hammer-head, a hammer-helve connected to said hammer-head at one end and pivoted to a relatively stationary part of the machine at its other end, means for holding a piston-ring in position for being hammered by said hammer-head, a loading device for said hammer-helve and a heart-cam adapted to move said loading device along said hammer-helve and actuated mechanically together with the 75 hammering machine, substantially as described.

4. A piston ring hammering machine comprising in combination, a hammer-head, 80 a hammer-helve connected thereto at one end and pivoted to a relatively stationary part of the machine at its other end, means for holding a piston-ring in position for being hammered by said hammer-head, and means for reciprocating said hammer-head, 85 a loading means for said hammer-helve, a guide for said loading device disposed approximately transversely of said helve, a bar carrying the said transverse guide and movable at right angles thereto, a member 90 on the bar for transmitting pressure thereto, a cam for imparting movement to said bar through said member, means for operating said cam and means for varying the length of movement imparted to said member, substantially as described.

5. A piston-ring hammering machine comprising in combination, a hammer-head, 100 a hammer-helve connected thereto at one end and pivoted to a relatively stationary part of the machine at its other end, means

for holding a piston ring in position for being hammered by said hammer-head, a loading means for said hammer-helve, means for varying the position of said loading means along said hammer-helve and means for reciprocating said hammer-head, a guide for said loading device disposed approximately transversely of said hammer-helve, a bar carrying the said transverse 110 guide and movable at right angles thereto, a bar-roller on said bar for transmitting pressure thereto from a cam working-surface and adjustable transversely of said bar, a bar-lever adapted to oscillate in contact with the tread of said bar-roller and a roller on the bar-lever adapted to make peripheral contact with said cam working-surface, substantially as described.

6. A piston ring hammering machine 125 comprising in combination, a hammer-head, a hammer-helve connected thereto at one end and pivoted to a relatively stationary part of the machine at its other end, a chuck for holding a piston-ring in position for 130

- being hammered by said hammer-head and comprising a chuck body, a bed-ring recessed annularly to receive a piston-ring, means for progressively rotating said bed-ring; a detachable cover-ring adapted to lie against the piston-ring in the bed-ring, a screw separate from the cover-ring and fixed to said bed-ring, a nut engaging said screw for applying pressure to and gripping said piston-ring between said bed-ring and said cover-ring and adapted to allow the detachment and removal of said cover-ring and piston-ring past said screw and nut when the pressure is relieved, a loading means for said hammer-helve, means for varying the position of said loading means along said hammer-helve and means for reciprocating said hammer-head, substantially as described.
- 20 7. A piston ring hammering machine comprising in combination, a hammer-head adapted to move in a straight line, a snail-cam and gearing operated together with the machine for reciprocating said hammer-head, a hammer-helve connected thereto at one end and pivoted to a stationary part of the machine at its other end, a chuck for holding a piston ring in position for being hammered by said hammer-head and comprising a chuck body, a bed-ring recessed 30 annularly to receive a piston ring, a detachable cover-ring adapted to lie against the piston ring in the bed-ring, a screw secured to said bed-ring at each of opposite ends of a diameter thereof, a nut engaging 35 each screw for applying pressure to said cover-ring so as to grip the piston-ring between said bed-ring and said cover-ring and so as to allow the detachment and removal of said cover-ring and piston-ring past the 40 screws and nuts when said pressure is relieved, toothed gearing for automatically and progressively rotating said bed-ring, a loading device for said hammer-helve, a guide for said loading device disposed transversely of said hammer-helve, a bar carrying the transverse guide and movable at right angles thereto, a bar roller on said bar and adjustable transversely thereof, a bar-lever in contact with the tread of said 50 bar-roller, a heart-cam, a bar-lever roller on said bar-lever adapted to make peripheral contact with said heart-cam working-surface and means for automatically arresting the operation of the machine, substantially 55 as described.

WILLIAM ARTHUR OUBRIDGE.
